LEON S. BRACH, OF NEW YORK, N. Y.

LIGHTNING-ARRESTER.

1,004,235.

Specification of Letters Patent. Patented Sept. 26, 1911.

Application filed October 5, 1909. Serial No. 521,085.

To all whom it may concern:

Be it known that I, LEON ST. CLAIR BRACH, residing at New York, in the county of New York and State of New York, have invented certain new and useful Improvements in Lightning-Arresters, of which the following is a specification.

This invention relates to lightning arresters, and one of the objects thereof is to provide improved connections and supports for the insulator which is interposed between the line and ground.

A further object is to provide in the line-to-ground connection an insulating member of very high resistance, and on either side of the same conductor members, the materials and relative arrangement of said members being such that the highest efficiency of contact is secured, while at the same time danger of interference with the insulating function of said intermediate member is avoided.

A further object is to provide a lightning arrester which is an efficient unity, and which is yet capable of being connected with a similar unit in such manner that they shall have a common ground, the several ground pieces of the units being brought into electrical connection at the same time with and by the mechanical connection of the units.

Further objects and aims of the invention, more or less broad, together with the advantages inherent, will be in part obvious and in part specifically adverted to in the course of the following description, wherein the elements, combinations, and arrangements of parts constituting the present invention will be fully set forth and the scope of the application thereof will be indicated in the appended claims.

Referring to the drawings, in which I have illustrated merely preferred forms of embodiment of the invention and its various contributing features: Figure 1 is a side elevation of a lightning arrester unit embodying my invention; Fig. 2 is a front view of a multiple unit lightning arrester, made up by the mechanical and electrical connection of two such units as is shown in Fig. 1; Fig. 3 is a top plan view of the subject view of Fig. 2; Fig. 4 is a detail perspective of the ground-plate, illustrating the interlocking members thereon; Fig. 5 is a view of another part of the line-to-ground connection, illustrating the means for sup-

porting the insulation; and Fig. 6 is a plan view illustrating a modification.

Referring now to the numerals on the drawings, 1 indicates a base, formed of a suitable insulating material, which is adapted to carry the other parts of a lightning arrester, preferably of some such shape as is shown.

The lightning arrester is adapted to be included in a line, as usual, and accordingly is provided with binding posts 2 and 3, for connection with the line. A conductor plate 4 extends between and is in electrical connection with the said binding posts, and the path of normal line currents is through said conductor.

5 indicates one member of the line-to-ground connection about to be described. Said member, shown in Fig. 5 in detail, preferably comprises a flat part 6, adapted to rest upon the line conductor 4, and apertured as at 7, for engagement with the binding post 2. Extending vertically from the part 6 is a member 8, which is provided with a punched-out-member 9, an over-hanging part 10, and side wings or flanges 11, which may be cut or punched to give the device substantially the form shown in Fig. 5, the space defined by said members 9, 10, and 11, being adapted to receive a carbon block or the like conductor hereinafter referred to, the carbon being thus in electrical union with the line-plate, though mechanically separable. The member 5 is preferably of resilient metal, and shaped and positioned so that when in place as in Fig. 1, the up-standing part 8 presses forwardly, away from the part 6. The purpose of this arrangement will be explained later.

12 indicates in a general way the ground-plate proper of my device, adapted to co-operate with the member 5 to hold between them the insulation which normally prevents a short circuit. Member 12 is preferably formed as indicated in Fig. 4, and comprises upright members 14 and 15, and a connecting piece 16. The member 12 is secured in position on the base 1 as by being screw-held thereon through the apertures 17, so that the connecting piece 16 is in opposed relation to the space between the parts, 9, 10, and 11 of member 5. In order that the ground plate may co-operate with the line-plate 5 in its function of supporting insulation between them, the member 12 is

provided with members 18 and 19, punched or cut out therefrom and adapted to mechanically and electrically engage a carbon block or the like, hereinafter described. 5 With insulation in place between the carbon blocks, as indicated in Fig. 1, the same will be held between the members 5 and 12, as clearly appears from said figure, and will be firmly though not positively held because 10 of the spring pressure of member 5, referred to above.

The ground-plate 12 constitutes the means of mechanically uniting several of the lightning arrester units, and to this end one of 15 the upright members, for instance 15, is provided with a recurved extension 20. As is well shown in Fig. 3, in assembling the units the side member 14 of one unit is engaged with the hook 20, thus forming a 20 mechanical union. It will be observed that the very fact of mechanical union brings about electrical connection between the ground-plates of the several units, so that only one connection need be made from 25 ground-plate to ground, irrespective of the number of lines which may under extraordinary conditions discharge through their respective ground-plates, I may provide member 14 with an aperture 21, while 30 provide a screw 22 that extends through the members of the hook 20, and then by tightening the screw, the parts may be promptly united together. Furthermore, as shown in Fig. 3, when the multiple unit has been built 35 up to the desired extent, the side of the hook, and the screw extending therethrough may be utilized as parts of a binding post 23, by which attachment may be made of a conductor from the ground-plate, or rather 40 plates 12, to the ground.

The manner of using the device as thus far described is believed to be obvious from the foregoing description of parts, and it is apparent that I have provided a very simple, efficient, and cheap lightning arrester 45 unit, which is easily assembled in multiplied series without the necessity for addition or subtraction or manipulation of parts.

Proceeding now to another aspect of this 50 invention, I shall consider the particular insulation which has been stated to be held between the line member 5 and the ground-plate 12. This insulation is preferably supported between two blocks 24 and 25 which 55 in turn are held within and by the appropriately formed parts of the line-plate and ground-plate as already described. Blocks 24 and 25 are preferably formed of carbon although I do not intend to limit myself 60 to such substance. For instance, graphite or similar material may be employed in this relation. Between said carbon blocks I provide an insulating block of carborundum 65 26. The carbon blocks being clamped upon the carborundum, and the latter being a

much harder material relatively, the surface carbon will enter the superficial interstices of the carborundum, thus bringing about the highest contact efficiency. It is of course immaterial whether the insulating member 70 be hard, and the conductors that engage it soft, or vice versa. It contemplates broadly the use of materials, of such relative qualities, and so united, that the superficial interstices of one are engaged by corresponding 75 parts of the other. At the same time the carborundum will effectually prevent short circuit from line to ground, except in the case of unusual currents on the line.

While I have described the contact blocks 80 24 and 25 as of carbon, and the insulating block 26 as of carborundum, I desire it to be understood that these materials are only typical. I contemplate the use of any high resistance material, but capable of withstanding without destruction or serious injury the passage of unusual currents, and on either side of said high resistance material, a material of conductive qualities, so united to the opposed surface of the insulating member that the maximum of surface contact is secured. For instance, I might use carborundum or the like, and on either side thereof some metal which has been superficially united to the opposite surfaces of 95 the carborundum or like member as by electrolytic deposit, or by being brought into contact therewith while in a molten state, or by the exercise of pressure. The purpose of the carborundum or like high resistance 100 material is in order that all possibility of any destruction of the insulation between the line and the ground may be avoided. If some insulator were used which would be destroyed or changed by the heat of abnormal currents, the material of the conductors on either side of the insulator, or the metal of the line-plate and ground-plate, might fuse and form a short circuit.

In Fig. 6 I have indicated a modification, 110 in which I interpose between the conductors 24 and 25, which are preferably of carbon, as already described, a pair of carborundum blocks 27 and 28, and between these latter is held a sheet of mica 29, or the like, in order 115 to more closely approximate a substantially perfect insulation.

As many changes could be made in the above construction and many apparently widely different embodiments of this invention could be made without departing from the scope thereof, it is intended that all matter contained in the above description or shown in the accompanying drawing shall be interpreted as illustrative and not in a 120 limiting sense. It is also to be understood that the language used in the following claims is intended to cover all of the generic and specific features of the invention herein described and all statements of the scope of 125 130

the invention, which as a matter of language, might be said to fall therebetween.

Having thus described my invention what I claim as new and desire to secure by Letters Patent, is:

1. In a device of the kind described, a pair of carbon blocks, a carborundum block between them and insulating the one from the other, and means for maintaining the 10 carbon blocks in contact with the carborundum block under pressure.

2. In a device of the kind described, a rigid carbon electrode, another carbon electrode spring-pressed toward the first, and a 15 carborundum block interposed between said electrodes.

3. In a device of the kind described, a high resistance member formed of relatively hard material, a member of relatively soft material and relatively good conductive qualities arranged at either side of said first named member, means for maintaining said members in close surface contact, and means for connecting one of said last named members 25 with ground.

4. In a device of the kind described, in combination, a ground plate, a pair of members of relatively good conductive qualities and of relatively soft material, an insulating 30 member of relatively high resistance qualities and relatively hard material interposed between said first named members, and a pair of opposed members, one of which is connected with said ground plate and the 35 other of which is adapted to be connected to a line, for holding said first named members in close surface contact with said high resistance material.

5. In a device of the kind described, in 40 combination, an insulating member of relatively hard material and of relatively high resistance qualities, provided with surface interstices, a pair of members of relatively soft material and relatively good conductive 45 qualities disposed at opposite sides of said first named member, means for pressing said last named members against said first named member so that the material of said last named members will enter the interstices of 50 the high resistance member, and means for connecting one of said pair of members with ground.

6. In a device of the kind described, a 55 pair of opposed electrodes, one of which comprises a spring member, an insulating member of relatively hard material and relatively high resistance qualities, provided with surface interstices, and a member of relatively good conductive qualities and relatively soft material adapted to engage with 60 said high resistance member, said members being interposed between said electrodes and

held thereby in close surface contact so that the material of the softer of said two members will enter the interstices of the other. 65

7. In a device of the kind described, in combination, a pair of opposed electrodes one of said electrodes being constituted by a spring, an insulating member formed of relatively hard material and relatively high resistance qualities, and a pair of members of relatively soft material and of relatively good conductive qualities disposed at opposite sides of said high resistance member, said three members being interposed between 75 said electrodes and held thereby in close surface contact so that the material of the softer members will enter the surface interstices of the harder member.

8. In a lightning arrester, a ground plate 80 having an integrally formed hook member and an integrally formed member adapted to enter a similarly formed hook member of another lightning arrester.

9. In a lightning arrester, a ground plate 85 having an integrally formed hook member, an integrally formed member adapted to enter a similarly formed hook member of another lightning arrester, and a screw threaded through the parts of said hook 90 member.

10. In a lightning arrester, a ground plate provided with an upstanding member having a reversely turned part, and a second upstanding member, the latter of which is 95 adapted to engage with a similarly formed reversely turned part of another lightning arrester.

11. In a lightning arrester, a ground plate provided with an upstanding member having a reversely turned part, a second upstanding member, the latter of which is adapted to engage with a similarly formed reversely turned part of another lightning arrester, and means for fastening together 100 105 the engaging parts of adjacent arresters.

12. A lightning arrester, comprising in combination, a ground plate provided with an upstanding member having a reversely turned part, a second upstanding member provided with a slot, said last named member being adapted to engage with a similarly formed reversely turned part of another lightning arrester, and a screw threaded 110 through the reversely turned part and extending through said slot for holding said parts together.

In witness whereof, I affix my signature in the presence of two witnesses.

LEON S. BRACH.
